Primary Examiner — Robert Delehanty*(74) Attorney, Agent, or Firm* — Banner & Witcoff, Ltd.(57) **CLAIM**

The ornamental design for a faucet, as shown and described.

DESCRIPTION

FIG. 1 is a front perspective view of a faucet showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the circular region on the handle in FIGS. 1 and 2, the interior of the base and spout opening in FIG. 7, and the ellipse-shaped region on the rear of the faucet in FIG. 3 is for environmental purposes only and forms no part of the claimed design.
